UNITED STATES PATENT OFFICE.

CHARLES B. HURST, OF ROSS COUNTY, OHIO.

FRAME FOR SCALES.

SPECIFICATION forming part of Letters Patent No. 767,690, dated August 16, 1904.

Application filed November 30, 1903. Serial No. 183,098. (No model.)

To all whom it may concern:

Be it known that I, CHARLES B. HURST, a citizen of the United States, residing near Chillicothe, in the county of Ross and State of Ohio, have invented certain new and useful Improvements in Frames for Scales, of which the following is a specification.

My invention relates to improvements in frames for wagon and stock scales; and the object of my invention is to provide a concrete or similar frame which can be cheaply built and easily transported and which can be placed in position and is immediately ready for use.

15 My invention consists in the constructions and combinations of parts hereinafter described, and set forth in the claims.

In the accompanying drawings, Figure 1 is a perspective view of my device shown in position on its foundation, one of the sections being removed to better illustrate some of the parts. Fig. 2 is a view in perspective of the end of one of the frame-sections, and Fig. 3 is a perspective view of the under side of same. Figs. 4, 5, and 6 are detail views of the connecting devices for the respective frame-sections. Fig. 7 is a view illustrating a method sometimes employed for building up a section for the purpose of enlarging the frame. Fig. 30 8 is a modification of the fastening-bands.

Like parts are represented by similar reference characters in the several views.

In building up the supporting-frames for wagon and stock scales steel and wood have 35 heretofore been employed for this purpose. The steel and wood frames, however, are expensive. Concrete frames built up at the place where the scale is to be installed are objectionable in that a considerable length of 40 time is required to allow them to become hard and firm enough to permit a heavy load to be placed on the platform of the scale and also owing to the weather conditions, which will prevent the construction of concrete frames 45 during certain seasons of the year. To overcome these objections, I have provided a concrete framework which is built in sections and shipped to the place where the scale is to be installed and have provided means for 50 surely joining these sections together in such

a manner that these frames can be made immediately ready to permit the scale to be put in use.

In the said drawings, *a a* represent the respective frame-sections, which are formed 55 from concrete or similar substance of a size which will be convenient for transportation. Both ends of the respective sections *a* are formed with rounded recesses *a'*, extending vertically the entire depth of the section, as 60 shown, so as to form a round vertical opening between the respective sections when they are placed together in position to form the frame. The extreme ends of the respective sections are preferably beveled, as shown at 65 *a''*, the adjacent ends of the sections being beveled in opposite directions, so as to correspond to and fit each other, and thus form a firmer joint between the respective sections. After the respective frame-sections are in position on their foundation I have provided means 70 for drawing the adjacent ends of the same firmly together. In each section *a* at the time of constructing the same is embedded a band *b*, formed at one end with an eye *b'*, which projects from one end of the section. The other end of the band *b* projects from the opposite end of the frame-section and receives a loose engaging hook *b''*. This end of the band is 75 also screw-threaded to receive an adjusting-nut *b'''* for said hook. When the sections are placed in position, the eye *b'* of one section 80 will be engaged with the hook *b''* of the adjacent section, and by turning up the nuts *b'''* of the respective rods the sections will all be 85 united firmly together, the respective bands forming substantially a continuous retaining-band. Also embedded in the respective sections are rods *c*, the ends of which project from the sections for a suitable distance and are 90 formed with projecting portions or hooks *c'*. I have shown two of these rods *c* for each section, one at the top and bottom at each side of the vertical center thereof; but more may be employed, if desired. When the respective sections are tightened together by the rods *b*, as described, the openings formed by the recesses *a'* are filled with plugs *d*, formed by tamping in concrete or similar material, and when this hardens the sections are thus 95 100

continuously and firmly joined together by reason of the projecting portions c' of the rods c , which become embedded in the concrete plugs d .

5. e represents the supports or connections for the platform-levers of the scale, which connections are held in position on the frame a by rods e' and nuts e^2 , which rods extend through the frame-sections a and are secured to anchor-rods e^3 , which extend to anchors e^4 , as shown, to take the strain of the scale-plate-form and the load thereon from the frame-sections.

In case it should be desired to enlarge the frame an additional section or sections may be provided by the means shown in Fig. 7. Two adjacent sections a are separated for a distance equal to the enlargement desired, the intervening space between the same inclosed by temporary walls f , as shown, and the space then filled by tamping in concrete, the connecting-bands b and the rods c being embedded in said concrete in the manner heretofore described, the said band b being first tightened up to the desired degree to form a continuation of the endless band formed by the rod-sections b , as described.

When the frame-sections are placed in position on their foundation, it is of course usual to provide an intervening layer of concrete or mortar between the said sections and the foundation. If desired, rods g may be provided, which are embedded in the respective frame-sections and extend from the bottom thereof and are provided with projecting portions g' , adapted to embed themselves in the concrete or mortar, and thus more firmly secure the same frame-sections in position.

In Fig. 8 I have shown a modification in the manner of joining together the bands b . In this construction the end of the band formed with the eye b' is bent at right angles to the band, and the eye is threaded over the end of the adjacent band, which is screwed threaded to receive the nut b^3 , which can be screwed up against the eye b' to tighten the bands.

Having thus described my invention, I claim—

50. 1. In a scale, a frame formed in sections of initially plastic material such as concrete, said sections being adapted to abut one against the other, recesses in the respective ends of said sections to form openings between the same, a band embedded in each of said sections with the ends thereof projecting into the respective openings, devices extending from one band connecting said band to the band in the opposing section, means for adjusting the connecting devices for the purpose of tightening said bands to form a continuous retaining-band for said frame-sections, and material similar to said frame-sections adapted to be tamped into the respective openings between said sections, substantially as specified.

2. In a scale, a frame formed in sections of plastic material such as concrete, recesses formed in the respective ends of said frame-sections to form vertical openings between the adjacent ends of said sections, rods embedded into said sections and adapted to project from the respective ends thereof into said openings, said rods having laterally-projecting portions at their ends, and plastic material such as concrete adapted to be tamped into said openings and embrace the laterally-projecting portions of said rods, for the purpose specified.

3. In a scale, a frame formed in sections of plastic material such as concrete, bands in said sections adapted to engage with each other to form a continuous retaining-band through said sections, means for tightening said bands, recesses formed in the respective ends of said sections to form a continuous vertical opening between the respective sections, plastic material such as concrete adapted to be tamped in said openings, and rods in addition to said retaining-band projecting from said sections having lateral projections adapted to be embedded in said plastic material, substantially as and for the purpose specified.

4. In a scale, a frame formed in sections of plastic material such as concrete, a band embedded in each of said sections formed at one end with an eye, and adjustable means at the opposite end of said band to engage the eye of the adjacent band, for the purpose specified.

5. In a scale, a frame therefor formed in sections of plastic material such as concrete, said sections being adapted to abut one against the other, a band embedded in each of said sections and rods embedded in each of said sections, one above said band and one below said band, adjustable means for connecting the ends of said bands, recesses formed in the respective ends of said frame-sections to form vertical openings between the adjacent ends of said sections, lateral projections formed on the ends of said rods and plastic material such as concrete adapted to be tamped into said openings and embrace the laterally-projecting ends of said rods and the ends of said bands after the same have been connected together.

6. In a scale, a frame formed in sections of plastic material such as concrete, recesses formed in the respective ends of said frame-sections to form vertical openings between the adjacent ends of said sections, a band embedded in each of said sections and adjustable means connecting the ends of said bands for forming a continuous retaining-band for said frame-sections, rods also embedded in said sections and adapted to project from the respective ends thereof into said openings, lateral projections formed on the ends of said rods, and plastic material such as concrete adapted to be tamped into said openings and embrace the laterally-projecting portions of

said rods for the purpose of holding said frame-sections in the position to which they have been adjusted by the adjusting means, for the purpose specified.

- 5 7. In a scale, a frame formed in sections of plastic material such as concrete, a band embedded in each of said sections, said band being screw-threaded at one end and provided at the other end with an eye bent at right angles to said band, said eye being adapted to be threaded over the screw-threaded end of

the adjacent band, and nuts on the screw-threaded ends of said bands, substantially as and for the purpose specified.

In testimony whereof I have hereunto set my hand this 25th day of November, A. D. 1903.
